JACOB ROME, OF PHILADELPHIA, PENNSYLVANIA, ASSIGNOR TO THE ALLEN-SHERMAN-HOFF COMPANY, A CORPORATION OF PENNSYLVANIA

NOZZLE OSCILLATING MEANS

Application filed May 31, 1929. Serial No. 367,281.

This invention relates to apparatus for ash disposal in large power plants by means of water jets and has among its objects the provision of a simplified form of such means, 5 relatively inexpensive to install, not likely to get out of order, and controlled by direct and simple outside connections.

My present invention relates more particularly to a construction of multiple oscillatable nozzles for use in connection with a hopper and sluiceway for handling ashes, the nozzles being joined together into a unitary structure adapted to be given oscillatory movement by a single simple connection to 15 direct water progressively against a pile of ashes on a feed plate and more or less parallel to the top surface of the latter.

In the present illustrative embodiment I disclose my invention applied in such a manner that the principal elements of the hydraulic system can be made of standard pipe fittings and other simple standard stock, although it is to be understood that the scope of my invention is not limited to the forms 25 herein shown and described.

A preferred form which I have selected for illustrative purposes is shown in the drawings herewith, wherein

Fig. 1 is a vertical longitudinal central section through a hopper and sluiceway in which my invention is embodied;

Fig. 2 is a vertical transverse section taken as indicated by the line 2—2, Fig. 1, looking in the direction of the arrows;

Fig. 3 is a top plan view of the nozzle assembly and its connections;

Fig. 4 is a side view of the nozzle assembly from the same point of view as Fig. 2;

Fig. 5 is a detail view, partly in section, of 40 the nozzle operating handle and connections; and

Fig. 6 is a front view of the nozzle assembly from the same point of view as Fig. 1.

In Figs. 1 and 2 I have shown an ash hopper 45 per 1 having a bottom formed in sections of which the sections 2, which form a baffle wall or walls, extend downwardly from intermediate the side walls but stop short of the latter, and of which the sections 3, the bottom walls proper, are walls extending down-

wardly from the side walls below sections 2 toward each other but with their adjacent ends spaced apart from each other. A grid or sizing screen 4 is positioned between the adjacent or lower ends of the walls 3 so 55 that ash washed off the walls 3 may pass therethrough to a sluiceway 7. The walls 2 and 3 are so disposed as to retain ash thereon. Means for removing accumulated ash from the walls 2 is shown at 5 which indicates a water line extending through the walls of the hopper to direct streams of water against the ash on the walls 2 to wash it therefrom. One embodiment of means for removing ash from the walls 3 is shown 60 in detail in Figs. 3 to 6 inclusive.

This embodiment of my invention consists of a plurality of water pipes 6 which extend through a wall 17 which, in the present instance, is a part of the wall hopper 1. The pipes 6 may be supported as by brackets 8 beneath the walls 2 and each pipe 6 is in communication with a depending pipe 9 having a pivotal or swingable connection 10. Each pipe 9 is preferably provided with a 75 nozzle 11 at its lower end, the two nozzles 11 extending in opposite directions and suitably disposed so as to direct streams of water against ash on both walls 3 and approximately parallel to the top surfaces 80 thereof.

Pipes 9 are joined together to move in unison by a plurality of clips 12. An operating handle or rod 13 is connected to the pipes 9 as by being attached to a clip 12, the 85 rod 13 extending through wall 17 and a cylindrical member 14 rotatably mounted in a suitable socket 15 on the wall. The members 14 and 15 serve to guide the rod 13 when the latter is being actuated to swing 90 the pipes 9 to the positions shown in Figs. 2 and 5 and direct streams of water progressively against the confronting surfaces of ash retained on the walls 3.

It will be understood that each pipe 6 is 95 preferably provided with a set of valves and that the pipes 6 may be connected to a single source of water under pressure or to two sources as may be desired.

When ash is to be removed from walls 3 100

water under pressure is admitted into pipes 6 and discharged through nozzles 11 against the ash on these walls. The rod 13 serves as a convenient single control means for 5 swinging both pipes 9 back and forth to direct the water from nozzles 11 against various parts of the surfaces of ash on the walls 3 so that the ash is washed from these walls progressively in amounts which can be read- 10 ily conducted away to a place of disposal by water travelling at high velocity in the sluiceway 7 from nozzle 16.

Many other structures embodying my in- 15 vention will doubtless occur to those skilled in the art so that I do not wish to be under- 20 stood as limiting my invention to the de- tails herein shown. The scope of my in- 25 vention is defined in what is claimed.

What is claimed is:

20. 1. Ash disposal means including walls spaced apart from each other for retaining ash, apparatus comprising in combination a sluiceway disposed in position to receive ash removed from the walls, a nozzle as- 25 semby including a plurality of pivotally suspended pipes having nozzles disposed between and above the tops of the said walls, means connecting said pipes together for conjoint movement, and guided means joined to the said pipes for swinging said pipes in unison about their pivots to direct water progressively against the ash on both walls.
30. 2. Ash disposal means including walls spaced apart from each other for retaining ash, apparatus comprising in combination a sluiceway disposed in position to receive ash removed from the walls, a nozzle assembly including a plurality of pivotally suspended 35 pipes having nozzles disposed between and above the tops of the said walls, means connecting said pipes together for conjoint movement, guided means joined to the said pipes for swinging said pipes in unison about their pivots to direct water progressively against the ash on both walls, and means for supplying water to said pipes.
40. 3. Ash handling apparatus comprising angularly disposed walls, a plurality of spaced apart walls on which ash may ac- 45 cumulate, means depending from said first named walls adapted to wash ash from said spaced walls, said means including a pipe for each of said spaced apart walls and pro- 50 vided with swingable connections and a noz- 55 zle positioned to direct a stream of water against ash on its respective wall and sub- 60 stantially parallel to the top thereof, the said pipes being joined together to swing in unison, and a guided rod connection to the pipes for swinging the pipes in unison.
65. 4. Ash handling apparatus comprising a hopper having angularly disposed baffle walls and spaced bottom walls on which ash 70 may accumulate, means depending from said

first named walls adapted to wash ash from said spaced bottom walls, said means in- 75 cluding a plurality of pivotally depending pipes, discharge nozzles oppositely and angularly disposed on the lower ends of said pipes and means, operable from outside of 80 the said hopper, for swinging said pipes to oscillate said nozzles.

5. Material handling apparatus including a hopper having bottom walls arranged to 75 provide a hopper discharge opening, a baf- 80 fle wall overlying said discharge opening and spaced above said bottom wall, means disposed below said baffle wall adapted for washing material from said bottom wall, 85 said means including pivotally suspended pipes having nozzles positioned to direct streams of liquid against material on said bottom wall, said pipes being disposed be- 90 neath said baffle wall and joined together 95 to swing in unison, means, operable from outside of said hopper, for swinging said pipes about their pivots, and means for sup- 100 plying liquid to said pipes.

6. Material handling apparatus comprising a hopper having angularly disposed baffle walls, spaced bottom walls disposed below said baffle walls and adapted to re- 105 ceive material from said baffle walls, means disposed below said baffle walls for washing material from said spaced bottom walls, said means including a pipe for each of said spaced bottom walls and provided with swingable connections and a nozzle posi- 110 tioned to direct a stream of liquid against material on each respective bottom wall por- 115 tion and substantially parallel to the top surface thereof, the said pipes being joined together to swing in unison, and a guided rod connection to the pipes for swinging the pipes in unison.

In testimony whereof I hereunto affix my signature this 27th day of May, 1929.

JACOB ROME.
